MATCH BOOK CASE

Gerhard M. Lee, Aurora, Ill.

Application November 11, 1936, Serial No. 110,377

4 Claims. (Cl. 206—33)

My invention relates to the disposition of matches, and includes among its objects and advantages the provision of an improved match book case designed to house conventional match books and in which means is incorporated to facilitate striking of the matches.

In the accompanying drawing:

Fig. 1 is a perspective view of the case;

Fig. 2 is a perspective view of the case in an open position;

Fig. 3 is a sectional view along the line 3—3 of Fig. 1;

Fig. 4 is a sectional view along the line 4—4 of Fig. 3;

Fig. 5 is a sectional view along the line 5—5 of Fig. 3;

Fig. 6 is a sectional view along the line 6—6 of Fig. 3; and

Fig. 7 is a sectional view along the line 7—7 of Fig. 6.

In the embodiment selected to illustrate my invention I make use of a case 10 comprising cover sections 12 and 14 hingedly connected together about an axis 16. The sections may be secured in closed position through the medium of a latch mechanism 18.

The covers 12 and 14 are identical in construction, each including a pocket 20 for frictionally retaining the butt end of a match book 22. In Fig. 3, I illustrate the match books as having their usual covers torn off along lines 24 so that the match inserts will carry their original abrasive surfaces 26, which surfaces are exposed through strike openings 28 in the covers 12 and 14.

In Figs. 2 and 3 it will be noted that the covers are so shaped as to snugly house two match books, but the covers have meeting edges 30 in their closed position so as to provide a complete enclosure for the matches. Each includes bored extensions 34 and 36. The extensions 34 are arranged in abutting relation with the extensions 36, but the former are spaced to accommodate a spring element 38 partly embracing a sleeve 40 mounted upon a pin 42 which passes through the aligned openings in the extensions 34 and 36 for hingedly connecting the covers 12 and 14.

In Fig. 3 I illustrate the spring element 38 as being bent to provide reaches 44 lying within the recesses 46 in the covers 12 and 14. The spring element 38 operates to automatically separate the covers 12 and 14 about their axis when the latch mechanism 18 is depressed.

Specifically, the latch mechanism 18 comprises a spring urged element 48 carried by the cover

section 12 and including a hook 50 co-operating with an abutment 52 for holding the covers in latched relation. A spring 54 normally holds the latch element in the position of Fig. 3, but the hook 50 may be moved out of latching relation with the abutment 52 by pressing the element 48 inwardly of the cover 12 against the tension of the spring 54.

Each cover is recessed at 56 to receive a block 58 pressed into the recess. These blocks are identical in construction so that the latch element 48 may be assembled with either of the two cover parts 12 or 14. The recesses 56 include extensions 60 for the reception of fingers 62 formed integrally with the blocks 58. These fingers hold the blocks 58 in spaced relation with the bottoms of the recesses as indicated at 64. The shank 66 which carries the hook 50 extends through the space 64 of the cover 12 and the hook is so aligned with the same space in the cover 14 as to move into the space when the covers are pressed together. I provide the hook 50 with a cam end 68 which rides over the abutment 52 when the covers are pressed together. The spring 54 is bowed and is restrained from lateral or longitudinal movement because of its location within the well 70.

It will thus be seen that the two cover parts are identical in construction and that the latch mechanism may be associated with either cover part. This feature facilitates assembly and eliminates the necessity for two differently constructed cover parts. All the parts of the hinge mechanism are effectively connected together by merely pushing the shaft 42 through the aligned openings in the extensions 34 and 36 and the sleeve 40. The spring 38 is easily assembled with the cover parts.

Because of the strike openings 28 the matches may be struck on the abrasive surfaces 26 after the cover parts have been closed. After all the matches in either book have been used a new book may be easily substituted by removing the connected end portions of the matches.

The covers 12 and 14 may be made of metal or composition.

Without further elaboration, the foregoing will so fully explain my invention that others may, by applying current knowledge, readily adapt the same for use under various conditions of service.

I claim:

1. A match case comprising two cover parts hingedly connected together, said cover parts being provided with openings, and socket means

positioned on the inner surfaces of said cover parts for frictionally retaining match books having abrasive surfaces, said openings being so positioned with respect to the socket means as to expose the abrasive on the match books.

2. A match case comprising two cover parts hingedly connected together, said cover parts being provided with openings, socket means positioned on the inner surfaces of said cover parts for frictionally retaining match books having abrasive surfaces, said openings being so positioned with respect to the socket means as to expose the abrasive on the match books, and latch means for holding the cover parts in closed relation.

3. A match case comprising two cover parts hingedly connected together, said cover parts being provided with openings, socket means po-

sitioned on the inner surfaces of said cover parts for frictionally retaining match books having abrasive surfaces, said openings being so positioned with respect to the socket means as to expose the abrasive on the match books, latch means for holding the cover parts in closed relation, and means for urging the cover parts to open positions when said latch means is released.

4. A match case comprising two cover parts hingedly connected together, each of said cover parts having an inner wall arranged in spaced relation with the cover to provide a socket for a match book, said inner walls being formed integrally with their respective cover parts, said cover parts being provided with openings opposite said inner walls for exposing abrasive on the match book.

GERHARD M. LEE.
